UNITED STATES PATENT OFFICE.

MARTHA A. BROCKWAY, OF BOSTON, MASSACHUSETTS.

DESIGN FOR A SPOOL.

SPECIFICATION forming part of Design No. 19,909, dated June 17, 1890.

Application filed May 8, 1890. Serial No. 351,087. Term of patent 14 years.

To all whom it may concern:

Be it known that I, MARTHA A. BROCKWAY, a citizen of the United States, and a resident of Boston, county of Suffolk, in the State of Massachusetts, have invented and produced a new and original Design for Spools, of which the following is a specification, reference being had to the accompanying drawing, forming a part thereof.

10 The drawing shows in perspective the spool embodying the invention.

The leading feature of my design for spools consists in the hollow cylindrical shank and square ends on said shank, the outer faces of the said ends being flat and their inner faces curved, the whole constituting a square-ended spool.

15 *a* represents the hollow cylindrical shank of the spool. *b* represents the square ends

on said cylindrical shank, the outer and inner faces of said ends being flat and curved, respectively. These square ends present to the eye a novel appearance, and the striking contrast is attractive.

20 I claim—

25 The design for spools herein shown and described, the same comprising a hollow cylindrical shank and square ends on said shank, the outer faces of said ends being flat and their inner faces curved, as set forth.

30 In testimony whereof I have signed my name to this specification in the presence of two subscribing witnesses.

MARTHA A. BROCKWAY.

Witnesses:

JAS. H. CHURCHILL,
EMMA J. BENNETT.
